UNITED STATES PATENT OFFICE.

EDWARD PICKETT, OF MEMPHIS, TENNESSEE.

SIGN.

Application filed September 17, 1927. Serial No. 220,209.

This invention relates to signs particularly serviceable for use in displaying advertising matter along highways, although capable of general use for advertising purposes 5 wherein a change in advertising matter is desirable.

More particularly, the present invention aims to provide a simple and practical form of frame for removably holding sign cards 10 or plates so that the latter will effectively remain in position while being capable of ready insertion or removal.

A further object is to provide a sign frame of the above kind which may be conveniently assembled or taken apart.

Still another object is to provide an improved sign holder including a supporting post and a sign frame so associated as to provide effective mounting of the frame and 20 to permit ready application of the frame to or removal of the same from the supporting post.

Other objects will become apparent as the nature of the invention is better understood, 25 and the same consists in the novel form, combination, and arrangement of parts hereinafter more fully described, shown in the accompanying drawings, and claimed.

In the drawing, wherein like reference 30 characters indicate corresponding parts throughout the several views,

Figure 1 is a perspective view, partly broken away, of a sign holder constructed in accordance with the present invention,

35 Figure 2 is a side elevational view thereof, Figure 3 is a horizontal section on line III—III of Figure 1,

Figure 4 is a horizontal section on line IV—IV of Figure 1, and

40 Figure 5 is an enlarged fragmentary vertical section taken on line V—V of Figure 1.

Referring more in detail to the drawing, the present invention embodies a frame for removably holding a plurality of sign plates 45 or cards, said frame being of rectangular form and embodying similar top and bottom frame plates or boards 5 and 6 and similar end plates or boards 7 having transverse grooves 8 in the ends thereof into 50 which the ends of the boards 5 and 6 are snugly fitted and suitably removably secured. In the form of construction shown, the frame also includes an intermediate horizontal frame plate or board 9 disposed parallel with and midway between the top and 55 bottom frame plates 5 and 6, and having its

ends snugly fitted and removably held in intermediate transverse grooves 10 provided in the inner faces of the end or side frame plates 7. A convenient manner of rigidly holding the frame members assembled may consist in driving screws through the side or end frame members 7 and into the ends of the frames 5, 6, and 9.

A pair of spaced parallel grooves 11 are 65 formed in the upper surface of the bottom frame plate 6 parallel with and adjacent the longitudinal edges of the latter, and provided in the under surface of the intermediate frame plate 9 are corresponding 70 grooves 12 which cooperate with the grooves 11 to form horizontal guideways adapted for removable sliding reception of suitable sign plates or cards, one of the guideways opening through one of the side frame members 75 7 by the provision of a vertical slot 13 in the latter, and the other guideway opening through the other side frame member 7 by the provision of a similar vertical slot 14 in the latter. The side frame members 80 7 have vertical grooves 15 formed in the inner surfaces thereof at the other ends of the guideways, respectively, to receive the ends of the sign plates or cards, when inserted. In a like manner, a pair of grooves 85 11^a are provided in the upper surface of the intermediate frame plate 9 adjacent to and parallel with the longitudinal edges of the latter, while similar parallel longitudinal grooves 12^a are formed in the under surface of the top frame plate 5 to cooperate with the grooves 11^a and form a pair of horizontal guideways for removable sliding reception of a further pair of sign cards or plates in the upper part of the frame, 90

Figure 5 is an enlarged fragmentary vertical section taken on line V—V of Figure 1. 95 Referring more in detail to the drawing, the present invention embodies a frame for removably holding a plurality of sign plates or cards, said frame being of rectangular form and embodying similar top and bottom frame plates or boards 5 and 6 and similar end plates or boards 7 having transverse grooves 8 in the ends thereof into 100 which the ends of the boards 5 and 6 are snugly fitted and suitably removably secured. In the form of construction shown, the frame also includes an intermediate horizontal frame plate or board 9 disposed parallel with and midway between the top and bottom frame plates 5 and 6, and having its 105 ends snugly fitted and removably held in intermediate transverse grooves 10 provided in the inner faces of the end or side frame plates 7. A convenient manner of rigidly holding the frame members assembled may consist in driving screws through the side or end frame members 7 and into the ends of the frames 5, 6, and 9.

110

the use of the side frame members interchangeably. In other words, the side frame members are identical or similar and adapted for interchangeable use at either side of the frame.

The above construction provides a very durable form of multiple sign plate holders, but it is evident that the intermediate member 9 may be eliminated together with the 10 slots 13^a and 14^a, so as to provide a sign frame for reception of only two signs, the slots 13 and 14 being in this case extended from the top frame member 5 to the bottom frame member 6 and likewise for the 15 grooves 15.

Means is provided for removably and effectively mounting or supporting the sign frame at the desired point along the highway, and this means consists of a suitable 20 supporting post 16 adapted to have its lower end suitably embedded and anchored in the ground as well as adapted to removably pass through and fit in vertical openings 17 provided in the bottom frame member 6 and intermediate frame member 9 and to have its 25 upper end abut the lower surface of the upper frame member 5 between the grooves 12^a. The openings 17 are provided intermediate the ends of the frame members 6 and 9 and between the grooves 11, 12 and 30 11^a. By reason of this construction, the frame may be readily lifted off of the post as well as placed thereon, and when in position on the post, the frame is effectively 35 supported against displacement and particularly against turning by reason of the angular form of the post and the openings 17. The lower end of post 16 preferably has outwardly projecting triangular anchoring fins 40 18 upon the sides thereof.

From the foregoing description it will be seen that I have provided a simple and durable form of sign plate or card holder in

which the sign plates or cards may be readily inserted or removed for effecting a 45 change in advertising matter. It will also be seen that the construction may be produced in a cheap and easy manner, while the parts may be conveniently and expeditiously assembled or taken apart without 50 the aid of special skill or tools.

Minor changes may be made without departing from the spirit and scope of the invention as claimed. For instance, only one side of the frame may be formed for reception of a sign plate or sign plates, while in cases where exceptionally long frames are employed, two or more spaced supporting posts may be used in an obvious manner. Moreover, the guideways may open through 55 the top and bottom of the frame instead of the sides thereof, and by using the proper type of sign plates, they may be illuminated by arranging the necessary source or sources of light within the frame in a general well-known manner. The necessary space for the latter purpose is provided for, by reason of the use of the wall boards in box-like formation, and this also permits ready 60 mounting of ornaments or road markers on 70 the sides of the frame.

What I claim as new is:

In a sign, a frame including side, upper and bottom wall boards, opposite ones of said wall boards having grooves in the inner 75 surfaces thereof parallel with and adjacent the longitudinal edges of the same to form guideways for removable slidable reception of sign plates, each of the remaining wall boards being provided with means to facilitate insertion of a sign plate into and removal of the same from one of said guideways.

In testimony whereof I affix my signature.

EDWARD PICKETT.
